UNITED STATES PATENT OFFICE

90,562

DESIGN FOR A CURTAIN OR THE LIKE

Max Sadinoff, Brooklyn, N. Y.

Application July 1, 1933. Serial No. 48,611

Term of patent 3½ years

To all whom it may concern:

Be it known that I, MAX SADINOFF, a citizen of the United States, residing at 1766 Union Street, in the borough of Brooklyn, city of New York, county of Kings, and State of New York, have invented a new, original, and ornamental Design for a Curtain or the like, of which the following is a specification, reference being had to the accompanying drawing, forming a part thereof.

The figure is a plan view of a curtain showing my new design. The surface ornamentation has been only partially shown in detail, it being un-

derstood that the ornamentation continues over the outlined portion of the curtain and the three-stepped vertical elements occurring only in the one corner as indicated. The broken away portion between the dotted lines shows a continuation of the design at the point of breakage.

I claim:

The ornamental design for a curtain or the like as shown and described.

In testimony whereof I have signed this specification.

MAX SADINOFF.
